BIRTH ANNOUNCEMENT PLAQUE

Joseph S. Wasko and Steve M. Wasko, Farrell, Pa.

Application January 10, 1951, Serial No. 13,739

Term of patent 14 years

(Cl. D29—23)

To all whom it may concern:

Be it known that we, Joseph S. Wasko and Steve M. Wasko, citizens of the United States, residing at Farrell, in the county of Mercer and State of Pennsylvania, have invented a new, original, and ornamental Design for Birth Announcement Plaque, for which the following is a specification, reference being had to the accompanying drawing, forming part thereof.

In the drawing:

Figures 1 and 2 are front and side elevations showing a birth announcement plaque embodying our new design;

We claim:

The ornamental design for a birth announcement plaque, substantially as shown.

JOSEPH S. WASKO.
